UNITED STATES PATENT OFFICE.

HILBERT L. FALK, OF NEW ORLEANS, LOUISIANA.

TELEPHONE SYSTEM.

Application filed September 23, 1921. Serial No. 502,760.

To all whom it may concern:

Be it known that I, HILBERT L. FALK, a citizen of the United States, residing in the city of New Orleans, parish of Orleans, State of Louisiana, have invented a new and useful Telephone System, of which the following is a specification.

The object and purpose of this invention is to provide a novel means for the transmission of speech, vocal or other sounds through a metallic conductor regardless of its length, resistance or capacity, without the employment of boosting relays or vacuum tubes interposed in the line between the transmitter and receiver, irrespective of the distance between said transmitter and receiver, means being also provided in my novel system for eliminating the employment of a return circuit or ground as commonly employed by the present commercial systems.

To accomplish these ends, I employ a novel arrangement of elements for the generation of an energy wave which is sent over the transmission line to the receiver regardless of the resistance in said line, and then transformed into direct electrical energy whereby no appreciable electrical current is permitted to pass into the transmitting lines.

I have found in the practice of my invention that the energy which I have generated will flow around any conductor regardless of its internal resistance or capacity.

I have further found from the practical use of my invention and it is my opinion based on extensive practical tests, that the size or length of said conductor regardless of the nature of the metal or resistance, offers no obstacle to the transmission of this energy, and I have further found in practice, that it is preferable to use iron or steel wire, which has a higher resistance than copper.

I have further found that by the use of a high resistance conductor, the transmission of the sound waves for proper reception is greatly improved and their audibility at the receiving end is more satisfactory. The novel theory by which I explain my invention is that of utilizing electrical energy to generate the novel magnetic flux or magnetic waves or lines of force I employ in the transmission of speech or other audible sounds, said magnetic flux being in turn thereafter transformed into direct electrical energy. My invention further consists of a novel provision to exclude all appreciable electric

oscillations and current from passing into the single transmission line.

I further provide novel means for permitting the transmission and reception of several messages at one and the same time over a single conductor.

I further provide novel means for transforming the energy, hereafter referred to, into direct electrical energy by the use of suitable novel instruments locally energized, thereby permitting the signals or sounds reproduced to become audible in an ordinary high resistance telephone receiver.

In my novel invention, as there is no appreciable electrical current in the line or conductor, it is my opinion based on the practical use of my invention that any electrical resistance therein can have no effect in the transmission of the energy hereinafter referred to, and as there is no appreciable electrical energy in the line, no return circuit or ground is required to accomplish my novel result.

To the above ends, my invention in its broad aspects consists of novel means for the transmission of speech, vocal or other sounds, wherein I employ a single ungrounded line extending between a plurality of stations, an energy transmitter at one of said stations, including a source of current variations and an energy transformer between it and said line, comprising means, including a resistance of the order of several megohms, and connections by which all appreciable electric oscillations and current are excluded, an energy receiver at the other station connected to the line, and means to reproduce from the received energy, current variations corresponding to those derived from said source.

It further consists of a novel construction of transmitter or transmitting system and receiver or receiver system, wherein vocal or other sounds are transmitted by energy hereinafter described, through a metallic conductor and then reconverted into direct electrical energy, thereby dispensing with boosting relays or vacuum tubes interposed in the line between the transmitter and receiver, and I further dispense with a return circuit or ground of the character commonly in vogue.

My invention further consists of other novel features of construction and advantage all as will be hereinafter fully set forth.

For the purpose of illustrating my invention, I have shown in the accompanying drawings, forms thereof which are at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a diagrammatic view of the transmitter of a telephone system embodying my invention.

Figure 2 represents a diagrammatic view of the receiver of a telephone system embodying my invention.

Figure 3 represents a detail view of the end secondary coils seen in Figure 1.

Figure 4 represents a detail view of the intermediate secondary coil seen in Figure 1.

Similar numerals of reference indicate corresponding parts.

Referring to the drawings:—

My novel invention in its entirety comprises a transmitting system and a receiving system, the construction and mode of operation of the transmitter being first described.

The novel elements entering into the transmitter are the following, reference being first had to Figure 1.

1 designates a soft iron core having the primary windings 2. The secondary windings which are three in number are designated as 3, 4 and 5.

The secondary winding 3 has the terminals 6 and 7 which are connected to the fixed condenser 8. The secondary winding 4 has the terminals 9 and 10 which are connected to the fixed condenser 11.

The secondary winding 5 has the terminals 12 and 13 connected to the fixed condenser 14, it being apparent that said secondary winding 4 acts as a check, thereby neutralizing the center of the coil, and prevents any current flowing between the coils 3 and 5.

It will be understood in practice that since the coil 4 has its terminals 9 and 10 connected to the fixed condenser 11, there is permitted a continuous flow of current in said coil within itself. The coil 4 is entirely disconnected from the coils 3 and 5, whereas in an ordinary induction coil, said coils 3, 4 and 5 would be connected.

In my device, the coils 3 and 5 are at opposite ends of the core, and consequently discharge opposite lines of force. The coil 4 being placed in the center, prevents any induced current between the coils 3 and 5, and said coil 4 generates within itself a current, preventing a unity of the coils 3 and 5 from generating an electric current

as commonly known within an induction coil.

Since the coils 3 and 5 have their terminals shunted across their respective condensers, it is impossible for an electric current to flow, as commonly known, to the lines 15 and 54, from either points 16 or 55 to be referred to. In Figure 3 I have shown the construction and mode of winding of the secondary coil 3, which is composed of fine insulated wire forming two coils, one half of the turns of one coil being wound clock wise as indicated at 130, and the other half of the turns of said coil being wound counter clock wise as at 131. The inner turns of the other coil start counter clock wise as indicated at 132, while the other half of the turns of said latter coil are wound clockwise as indicated at 133. From this construction it will be seen that the induced current generated within the secondary coil 3, reverses itself within that coil, and hence any current is prevented from flowing from said coil, and consequently only the magnetic waves or magnetic flux heretofore described flow from said coil 3 at the point 16 to the line 15. The terminals 6 and 7 are connected in series to the condenser 8, the purpose of which is to cause a circulation between the two coils composing the secondary coil 3, and to prevent leakage of energy.

The coil 5 has the same construction and function as the coil 3, so that as above described, the positive lines of force flow from the point 55 and the negative lines of force from the point 16.

The construction of the intermediate coil 4 will be understood from Figure 4, its inner turns starting counter clockwise as indicated at 134 and its outer turns 135 being clockwise, the inner and outer terminals 10 and 9 being shunted by the condenser 11, having the function already explained, of preventing leakage of energy. The line 15 is connected to the center of the coil 3 at the point 16, and extends to the fixed condenser 17 and extends therefrom to the high resistance coil 18 which is within the vacuum tube 19, which is a glass bulb, which has been highly exhausted to form a vacuum. The line 15 conveys only a negative magnetic wave, while the line 54 to be referred to conveys only a positive magnetic wave, since it is well known that an electromagnetic core when energized by an electric current becomes negative at one end and positive at the other, but after said waves have passed through the tube 19, they are rectified and become neutral and polarless and are devoid of any of the characteristics of an electric current. The resistance coil 18 is a wire coil of preferably tungsten metal, which is well known because of its high resistance, and is not to

be confounded with the customary grid-member of a vacuum tube.

The line 20 extends from the line 15 to the switch 21 from which leads the line 5 22 to the crystal rectifier 23, from which leads the line 24 to the direct current battery 25.

- From the lines 22 and 24 lead the lines 26 and 27 respectively to the fixed condenser 28.
- 10 The line 29 leads from the direct current battery 25 to the line 30 which leads to the negative magnetic plate 31 in the vacuum 19. The line 30 is connected to the high resistance coil 32 of six megohms. The line 15 33 leads from the resistance 32 to the fixed condenser 34, from which leads the line 25 to the primary inductance 36, from which leads the line 37 to the high resistance coil 38 of six megohms from which the line 39 20 leads to the secondary inductance 40, the line 41 leading from the latter to the receiving instrument.

The line 42 leads from the high resistance coil 32 to the direct current battery 43 of 25 about 20 volts, said battery being in series with the resistance 32 and the negative plate 31. The line 44 leads from the line 42 to the fixed condenser 45 from which leads the line 46 to the line 30. The line 47 leads 30 from the direct current battery 43 and the line 48 leads therefrom to the heating filament 49 in the vacuum 19.

The line 50 leads from the heating filament 49 to the rheostat 51 from which 35 leads the line 52 to the direct current battery 53. The line 54 leads from the rheostat line 52 and the battery 53 to the point 55 of the secondary winding 5.

- The line 56 leads from the line 54 to the 40 fixed condenser 57 from which leads the line 58 to the positive magnetic plate 59 in the vacuum 19. The line 60 leads from the line 15 to the plate 61 located in the vacuum 19. In practice, I have found the best 45 results to be obtained by making the positive and negative magnetic plates as 59 and 31 out of suitable magnetic metal, such as iron or steel, which is highly tempered in order to retain its magnetism. The positive plate 50 59 is coated on one side with a plate of silicon and the negative plate 31 is coated on one side with a plate of galena, the silicon and galena facing. The oscillating plate 61 is composed of platinum. The line 55 62 leads from the line 15 to the variable condenser 63 from which the line 64 leads to the line 54. I have found in the practical use of my invention that owing to static conditions, there may be a very 60 slight amount of static or atmospheric current in the line, which I particularly desire to prevent and consequently employ at the points designated the condensers 63, 17, 45, 57 and 28, whose capacities vary according to 65 climatic conditions from about two micro-

farads up, consequently, as a result of my employment of said condensers at the points indicated all liability of the presence of any appreciable electric or static currents in the transmission line 41 is positively prevented. 70

The condensers in the receiving system to be hereafter referred to are employed for the above reasons.

The telephone transmitter is indicated at 65 and is connected across the primary winding 2 in series with a direct current battery 66, it being apparent that the soft iron core 1 is separated from the coils 3 4 and 5 by the insulating tube 67.

It will be seen from the foregoing that the primary coil 2 is insulated from the secondary coils 3, 4 and 5 by the insulating material 67 and is connected in series with a suitable source of electrical current and telephone transmitter for the transmission of 80 speech and other sounds. The primary when in operation in my opinion sets up magnetic lines of force, without the secondary coils 3 and 5, which it will be noted are separated by another coil 4, at the neutral center of the primary coil. This coil 4 acts as a check, holding the negative and positive ends of the coils 3 and 5 to their respective polarity, thus allowing the negative lines of force to flow from the point 16 90 through the line 15 and fixed condenser 17, to the resistance coil 18 in the vacuum 19.

It is my opinion based on the practical use of my invention that by the employment of the coil 5, the positive lines of force flow 100 from the point 55 through the line 54 to the line 56, fixed condenser 57 and line 58 to the positive magnetic plate 59, located within the vacuum 19, and consequently the positive and negative lines of force within the 105 vacuum 19 are therein transformed into a magnetic wave without polarity, by the aid of the plate 61, which is connected to the circuit 15 by the line 60. No artificial means are used to oscillate the plate 61, which receives its movement from the negative lines of force in the line 60. I collocate the oscillating plate 61, the positive plate 59, the resistance coil 18, the filament 49 and the negative plate 31 within the vacuum tube 19 in 110 the order stated, and the phenomena occurring between the positive and negative plate may be likened in part to that which takes place between two mirrors facing each other and reflecting from one to the other, the energy conveyed to the tube by the resistance coil 18 positioned between said plates. The filament 49 is the only element within the tube which is hot, the other elements remaining comparatively cool. This vacuum 115 tube 19 is energized by a local electrical battery 53, which excites the filament 49, thereby creating heat within the vacuum, thus producing a wave which I call a magnetic wave, or magnetic flux, which is taken up by 120

125

130

the negative magnetic plate 31 and travels on the lines 30 and 33, fixed condenser 34, line 35, primary inductance 36, line 37, high resistance 38 and line 39 to the secondary inductance 40, and thence to the line 41 to the receiver. When the magnetic wave above explained is created and travelling through the vacuum 19 as above explained the switch 21 is open. When the switch 21 is closed, 10 and the current is cut off from the filament 49 by the rheostat 51, the negative lines of force flow through the lines 20, 22, the rectifier 23, line 24, battery 25, and line 29 to the line 30. The shunt circuit last described is 15 utilized in case the filament 49 becomes burnt out or destroyed, and it will be apparent that by the manipulation of the switch 21, the circuits last described can be used independently or in combination, and when 20 used in combination, it will be evident that the magnetic waves are intensified, since there is a double unit functioning. It is possible to start the system into operation by closing the switch 21, without heating the 25 filament 49, the filament not being an essential element to start the system, but when the switch 21 is open, the filament is essential.

The lines 26 and 27 connect the fixed condenser 28, whose function is to absorb static energy. The line 42 leads from the high resistance 32 to the direct current battery 43 and through lines 47 and 48 to the filament 49, whereby there is caused in my opinion a movement of electrons within the vacuum 19, between the filament and negative plate 31, which movement causes the magnetic lines of force to flow through negative magnetic plate 31, to the line 30, and thence 30 as above described to the line 41. It will be particularly noted that by the employment of the six megohms resistance 32 at the point indicated, no appreciable current is permitted to flow from the battery 43 to the negative magnetic plate 31, within the vacuum 19, as in ordinary practice where there is no resistance as at the point 32. By the above 40 novel construction, I permit only magnetic waves to pass between filament 49 and the negative magnetic plate 31. If the resistance 32 were removed electric current would flow between filament 49 and plate 31, which I particularly desire to avoid, and especial attention is called to this feature of my invention which consists in employing said resistance 32, since by this device, I have eliminated any necessity for the employment of a return circuit, since only magnetic waves or lines of force flow into the transmission 50 line 41.

The fixed condenser 45, which is connected to the lines 30 and 42 by the lines 46 and 44 respectively, is used for properly balancing the circuit. The variable condenser 63, 60 which is connected to the lines 15 and 54 by

the lines 62 and 64, is used for the purpose of balancing the discharge from the coils 3 and 5. By the term "balancing" I mean that the magnetic waves in the lines 15 and 54 are of the same capacity or of equal strength. 70 The plate 61 which is connected to the line 15 through line 60 in my opinion causes a churning or agitating of the magnetic waves within the vacuum 19, thereby keeping them in constant motion thereby generating what 75 I term a polarless magnetic wave, which is taken to the line 30 by the negative magnetic plate 31. The function of the condenser 8 is to prevent a short circuit between the terminals 6 and 7 of the coil 3, it being 80 my opinion that no current leaves the coil 3, and only the form of energy which I term magnetic waves leaves said coil at the point 16.

The function of the condenser 14 of the 85 coil 5 is to prevent a short circuit between the terminals 12 and 13 of said coil, it being apparent that as in the case of coil 3, no current leaves coil 5, and only the form of energy which I term magnetic waves leaves 90 said coil 5 at the point 55. The condenser 11 in the coil 4 prevents a short circuit between the terminals 9 and 10, and the energy generated within said coil 4 circulates with 95 in said coil, thereby having a neutralizing effect on its center and between the coils 3 and 5, thus making it possible for the waves discharged from the coils 3 and 5 to retain their individual polarity opposite to each other. 100

The condenser 17 located in the line 15 prevents any possibility of any electrical energy passing to the high resistance coil 18 in the vacuum 19, since no appreciable alternating current whatever is ever present in 105 the system.

The operation of the transmitter system above described is as follows, it being understood that the descriptions of the functions or phenomena hereinbefore referred to and hereinafter described, in respect of my novel apparatus are offered as an hypothesis. It will be further understood that the terms magnetic wave, magnetic flux, positive lines of force, negative lines of force and polarless magnetic wave or flux as employed herein as definitive of the energy transformations occurring in my novel apparatus, constitute a nomenclature, for these elements devised by me and which so far as I am aware, I am the first to employ in connection with an apparatus of this character, and my claims to said apparatus are to be construed in accordance with the breadth accorded to pioneer inventions of this character and without regard to the hypothesis aforesaid. 110 120 125

Any audible sound passing into the transmitter 65 sets up a magnetic field in the primary coil 2, which is then taken up by coils 130

3 and 5, which then generate negative and positive magnetic waves, as above described, which, passing through their respective circuits into the vacuum 19 are changed into a 5 single polarless magnetic wave, which leaves the system by the line 41, and overcomes all resistance within the line between the transmitter and receiver, which is the opposite of what would occur if electric current was being used within this line. Resistance has no 10 effect in retarding the movement of this novel magnetic wave I have above described and I also eliminate the use of a return circuit as commonly employed in all electrical 15 circuits.

The magnetic wave heretofore described having been created and transmitted to the line 41, passes to the receiver 68 seen in Figure 2, whose construction and mode of operation will now be described. The line 41 is connected to the condenser 69 from which the line 70 leads to the coil 71, which is made variable by the adjustable contact 72. 73 designates a line leading from the coil 71 to the fixed condenser 74 from which leads the line 75 to the coil 76, which has the adjustable contact 77. From the coil 76 leads the line 78 to the oscillating plate 79 located in the vacuum 80.

30 81. designates a resistance coil within the vacuum 80, from which leads the line 82 to the fixed condenser 83 from which leads the line 84 to the coil 85, through the adjustable contact 86.

35 87 designates the line leading from the coil 85 to the line 88, which leads to the high resistance 89 of twelve megohms from which leads the line 90 to the line 78. The line 87 leads to the line 91 which is connected to the 40 rheostat 92, from which leads the line 93 to the filament 94, from which leads the line 95 to the line 96, which leads to the battery 97 and also to the battery 98, from which the line 99 leads to the telephone receiver 45 100, from which leads the line 101 to the adjustable impedance 102.

103 designates a line leading from the impedance 102 to the negative magnetic plate 104, located in the vacuum 80.

50 105 designates a line leading from the line 103 to the battery 106, from which leads the line 107 to the crystal rectifier or wave detector 108, from which leads the line 109 to the switch 110, which is connected by the 55 line 111 to the line 82.

112 designates a line leading from the line 109 to the fixed condenser 113, from which leads the line 114 to the line 78.

115 designates a line leading from the line 60 82 to the resistance 116 of two megohms from which leads the line 117 to the line 84.

118 designates a line leading from the line 78 to the fixed condenser 119 from which leads the line 120 to the positive magnetic plate 121, located in the vacuum 80. 122

designates a line leading from the line 78 to the fixed condenser 123, from which leads the line 124 to the line 75. 125 designates a line leading from the line 101 to the variable condenser 126, from which leads the line 127 to the line 99.

128 designates an insulating or separating medium between the coils 71 and 85, and 129 designates a similar insulating or separating medium between the coils 85 and 76.

It will be understood that in practice that the coils 71, 85 and 76 are wound one upon the other, the coil 76 being the inner coil, and the coil 85 wound thereupon but insulated 80 therefrom by the insulation 129. The coil 71 is wound on the coil 85 but insulated therefrom by the insulation 128. In practice, I construct these three coils of steel wire, since by this construction said coils 85 become magnetized by the magnetic wave or magnetic flux entering on the line 70 after passing through the fixed condenser 69, the capacity of each of said coils being made variable by the variable contacts 72, 86 and 90 95 77 respectively, and said three coils in practice becoming magnetized to a greater or lesser degree according to the variations in the incoming signals. These three coils having become magnetized in accordance with the density of the incoming magnetic waves or flux, it is my opinion that the variations of the magnetic lines of force causes a current to flow from said coil 71 through the line 73, condenser 74, line 75 into coil 76, line 78 to the oscillating plate 79 in the vacuum 80. Simultaneously a current is flowing from each end of the coil 85, through the line 84, condenser 83 and line 82 to the resistance 81 in the vacuum 80, and also through the line 87 to the line 91. Current is also flowing from line 78, through line 118, condenser 119 and line 120 to the positive magnetic plate 121.

The circuit composed of the lines 78 and 87 is balanced by the lines 88 and 90 having the resistance 89 therein of twelve megohms. The lines 78 and 75 above referred to are balanced by the lines 122 and 124 having the condenser 123 therein. By the provision of the heating filament 94 in the vacuum 80, it is my opinion that a movement of the negative electrons from the filament to the negative magnetic plate 104 is caused to take place and a direct current 110 flows through the line 103 to the impedance 102 and line 101 to the receiver 100 and by line 99 to the battery 98, line 96 and line 95 to the filament 94, line 93, rheostat 92 and line 91 to the battery 97. It is my opinion 115 that the magnetic wave or magnetic flux entering the receiver 68 by the line 70 is transformed into lines of force by the coils and their circuits, and thereby initially generated into electrical energy, the process 120 125 130 being

ing completed by the coating elements in the vacuum 80 and the polarless magnetic wave is thus transformed back into a direct current, which leaves said vacuum by the line 103, and imparts to the diaphragm of the receiver 100 vibrations conforming to the vibrations of the transmitter diaphragm 65.

By the provision of the lines 115 and 117 having the two megohm resistance therein, a leakage across the condenser 83 is permitted, which I have found to be desirable for the efficient operation of my invention. In case the filament 94 becomes dead or 15 burnt out, I close the switch 110 and utilize the circuit composed of the lines 111, 112, 109, the crystal rectifier 108, the line 107, the battery 106, and line 105, to take the place of the heated filament, it being apparent that if desired the last described circuit may be used in conjunction with said filament or separate therefrom.

By the condenser 113, in the lines 112 and 114, the oscillating plate circuit is balanced. 25 The variable condenser 126 is used in the lines 125 and 127 for regulating the variations of the vibrations of the diaphragm in the receiver 100.

It is my opinion, based on observing the practical operation of my device for a long period that in my novel system, the direct current created by the audible sounds in the transmitter is transformed by means of the secondary coils 3, 4 and 5, constructed or collocated as above explained into lines of force or a magnetic wave or a magnetic flux, which is employed for the transmission of such sounds, said flux being in turn generated into a polarless wave in the vacuum 19, which leaves said vacuum through the line 30 and after travelling over the line 41, and passing the condenser 69 and over line 70 is transformed by the elements intermediate the line 70 and the line 45 103 into a direct current again, leaving said vacuum 80 by the line 103, whereby the vocal or other sounds entering the transmitter 65, seen at the left of Figure 1, are reproduced in the receiver 100, seen at the right of Figure 2, so that the vibrations of the diaphragm of the receiver 100 conform precisely to the vibrations of the diaphragm of the transmitter 65.

I have found from numerous tests extending over a long period of time by standard commercial measuring instruments of the highest known delicacy and sensitiveness for the presence of electric oscillations and current, and it is my opinion, 55 that by my employment of the six megohm resistance 32, at the point indicated in Fig. 1, I prevent any appreciable electrical current from passing into the transmission line 41 since the novel form of energy 60 65 which I term a polarless magnetic wave or

magnetic flux only is permitted to pass to said line 41 in transmission, thereby overcoming all electrical resistance, since I provide means for so altering the magnetic wave as generated into distinct waves, thereby permitting the transmission and reception of several messages at one and the same time over a single conductor in telephony, as it is well known that magnetic lines of force are not affected by the resistance of the conductor.

It consequently follows that as there is no appreciable electrical current in the line, electrical resistance can have no effect on the transmission of the magnetic wave and as there is not appreciable electrical energy in the line, no return circuit or ground is required to accomplish the novel results that I have attained.

My novel system is in my opinion adapted especially for long distance or under sea telephony, and it is my opinion that in the practical use of my device direct current in the manner described is first generated, then transformed into energy having the characteristics hereinbefore described, which is finally transformed into direct electrical energy in the vacuum 80, so that only a direct current leaves said vacuum 80 by the line 103 and in practice audible telephonic spoken sounds or articulate speech have been clearly and distinctly reproduced by me in the above described system equipped with a transmitter and receiver of my invention, through a resistance and capacity equal to twenty five thousand miles, without boosting relays, return circuit or ground.

As heretofore explained, the resistance 32 of six megohms, is located in the circuit, as shown to prevent any flow of current from the battery 43 to the line 30 and I have found from the practical use of my invention that the omission of either the resistance 32 or the battery 43 or both from the transmitter will render the system inoperative.

I have further found from the practical use of my device that only a resistance of six megohms installed at the point 32 will produce the novel results heretofore described, since such practical use has shown that if the resistance 32 is increased or decreased beyond six megohms, the transmitter system becomes inoperative. I have also found from practical use that it is essential to get the best results that the resistance 32 be of six megohms and located at the point indicated. I have also found that in order to get the most efficient results in the receiver system, that the balancing resistance 89 therein should be twelve megohms and that the resistance 116 should be two megohms.

For the reason that this energy can be

transformed back to a direct electric current, as it originally started, I have reached the conclusion that a form of magnetic energy is present, and I have consequently adopted the nomenclature aforesaid. I am the first in the art to disclose the means herein described for the transmission of intelligence through a metallic conductor, without appreciable electric current in said conductor and without a return circuit or ground and without the employment of boosting relays, vacuum tubes or amplifiers of any character interposed in the line between the transmitter and receiver and without any appreciable alternating current in the system.

As I am the first in the art to disclose an apparatus for the transmission of intelligence having features of the character hereinbefore described, my claims to these features are to be interpreted with the scope awarded to pioneer inventions of this character.

It will be understood that the vacuum tubes 19 and 80 employed in the transmitter and receiver system respectively, together with their contents or coating elements are duplicates, so that a single standard size of vacuum tubes and its adjuncts can be employed in my invention the action and function of each of said vacuum tubes being identical, as has been heretofore explained.

It will be apparent to those skilled in the art that my invention, by reason of dispensing with relays, vacuum tubes intermediate the transmitter and receiver and the return circuits, possesses many elements of cheapness and advantage over the present systems of telephony now in vogue, since by dispensing with the intermediate relays and vacuum tubes, I am enabled first to have a direct connection between the transmitter and receiver; second, by dispensing with relays I eliminate the expense not only of the first cost of the relays, but in addition, the expense in the maintenance of said relays both in electrical energy as well as the labor of maintenance which amounts to a very considerable item; third, by eliminating a return circuit I consequently save the expense of a double wire; and fourth I have found that the power required in my device is considerably less than the power required in the present methods or systems of telephony now in vogue.

It will now be apparent that I have devised a novel and useful telephone system, which embodies the features of advantage enumerated as desirable in the statement of the invention and the above description, and while I have, in the present instance, shown and described a preferred embodiment thereof which will give in practice satisfactory and reliable results, it is to be un-

derstood that the same is susceptible of modification in various particulars without departing from the spirit or scope of the invention or sacrificing any of its advantages.

Having thus described my invention, what I claim as new and desire to secure by Letters Patent is:—

1. In a system for transmitting intelligence, a plurality of communicating stations, a single ungrounded line extending between said stations, an energy transmitter at one of said stations, including a source of current variations, an energy transformer between it and the line, comprising means including a resistance of the order of several megohms and connections by which all appreciable electric oscillations and current are excluded, an energy receiver at the other station connected to the line, and means to reproduce from the received energy, current variations corresponding to those derived from said source.

2. In a system for transmitting intelligence, a plurality of communicating stations, a single ungrounded line extending between said stations, an energy transmitter at one of said stations including a telephone transmitter, and an energy transformer having a primary conductively connected to said transmitter and a plurality of secondary circuits completed independently of one another, two of which are formed with their half windings oppositely wound so as to neutralize electric effects induced therein, means to connect said transformer to the line through a resistance of the order of six megohms, said means comprising conductors leading respectively to the junction points of the opposed half windings, and a telephone receiver at the other station connected to the line by means to reproduce from the received energy current variations corresponding to those derived from the telephone transmitter.

3. In a device of the character stated, a transmitter, an energy transformer, having a primary conductively connected to said transmitter, and comprising a secondary coil, a vacuum tube having therein a platinum plate, a positive magnetic plate coated with silicon, a resistance coil, a filament and a negative magnetic plate coated with galena, a line leading from said secondary coil to said platinum plate and said resistance coil, another line leading from said secondary coil to said silicon coated magnetic plate and a line leading from said tube from said galena coated magnetic plate.

4. In a device of the character stated, a transmitter, an energy transformer, having a primary conductively connected to said transmitter, and comprising a secondary coil, a vacuum tube containing a platinum plate, a plate of magnetic material coated

- with silicon, a resistance coil, a filament, and another plate of magnetic material coated with galena, a line leading from said secondary coil to said resistance coil and platinum plate, another line leading from said secondary coil to said silicon coated plate, and a line connecting said lines from said secondary coil and having a variable condenser therein.
- 5 10. 5. In a device of the character stated, a transmitter, an energy transformer, having a primary conductively connected to said transmitter, and comprising a secondary coil, a vacuum tube containing a resistance coil, a filament and a plurality of plates, two of which are composed of magnetic material, a connection from said secondary coil to said resistance coil and one of said plates, another connection from said secondary coil 15 to one of said magnetic plates, a line leading out from said tube from the other of said magnetic plates and means comprising a resistance of the order of several megohms for excluding all appreciable electric oscillations and current from said last mentioned line.
- 20 6. In a device of the character stated, a transmitter, an energy transformer, having a primary conductively connected to said transmitter, and comprising a secondary coil, a vacuum tube containing a platinum plate, a magnetic plate coated with silicon, a resistance coil, a filament, and a magnetic plate coated with galena, connections from 25 said secondary coil and to said platinum plate and resistance coil and another connection from said secondary coil to said silicon coated plate, a line having a variable condenser therein common to said last mentioned connections from said secondary coil, a line leading from said galena coated plate, and means for excluding all appreciable electrical oscillations and current from said last mentioned line.
- 30 40 7. In a system of the class described, a vacuum tube having therein a platinum plate, a silicon coated magnetic plate, a resistance coil, a filament and a galena coated magnetic plate, in combination with a secondary coil, and connections therefrom to said platinum plate, said silicon coated magnetic plate and said resistance.
- 35 45 8. In a system of the class described, a vacuum tube having therein a platinum plate, a silicon coated magnetic plate, a resistance coil, a filament and a galena coated magnetic plate, in combination with a secondary coil, connections therefrom to said platinum plate, said silicon coated magnetic plate and said resistance, and a line connected to said resistance, and having therein in a crystal rectifier and a battery.
- 50 55 60 65 9. In a system of the class described, a vacuum tube having therein a platinum plate, a silicon coated magnetic plate, a
- resistance, a filament and a galena coated magnetic plate in combination with a secondary coil, connections therefrom to said platinum plate, said silicon coated magnetic plate and said resistance, a line connected to said resistance and having therein a crystal rectifier and a battery, and a switch in said last-mentioned line, whereby the crystal rectifier and battery can be used independently or simultaneously with the line leading to said vacuum.
- 70 10. In a system of the class described an energy transformer comprising a secondary coil composed of a plurality of independent coils and an intermediate coil, all of said coils being composed of turns wound one half clockwise and the other half wound counterclockwise, and the terminals of each of said coils leading to a condenser.
- 75 11. In a system of the class described an energy transformer, comprising a secondary coil composed of two independent coils and an intermediate coil, all of said coils being composed of turns wound one half clockwise and the other half counterclockwise, condensers for the terminals of each of said coils, and lines leading from said independent coils.
- 80 12. The combination of a primary coil, a transmitter in series therewith, a secondary coil, the latter being composed of independent coils each composed of turns, half of which are wound clockwise and the other half counter clockwise, and an intermediate coil similarly wound, the terminals of said plurality of coils composing said secondary coil leading to condensers, a vacuum tube and lines leading from points of said secondary coil to said vacuum tube, the latter containing a resistance coil, a filament and a plurality of plates two of which are of magnetic material.
- 85 13. In a system of the class described, an energy transformer, a transmission line leading from said energy transformer, a variable magnetic coil 71 to which said line leads, another variable magnetic coil 76, a line leading from coil 71 to coil 76, a vacuum tube, a platinum plate therein, a line 78 leading from said coil 76 to said platinum plate, a resistance in said vacuum, another variable magnetic coil 85, a line 84 leading therefrom to said resistance, a silicon coated magnetic plate in said vacuum, a line leading from said line 78 to said silicon coated magnetic plate, a filament in said vacuum tube, a line 87 leading from said coil 85 to said filament, a galena coated magnetic plate in said vacuum, and a line leading therefrom to a receiver.
- 90 14. In a system of the class described, an energy transformer, a transmission line leading from said energy transformer, a variable magnetic coil 71 to which said line leads, another variable magnetic coil 76, a

line leading from coil 71 to coil 76, a vacuum tube, a platinum plate therein, a line 78 leading from said coil 76 to said platinum plate, a resistance in said vacuum tube, another variable magnetic coil 85, a line 84 leading therefrom to said resistance, a silicon coated magnetic plate in said vacuum, a line leading from said line 78 to said silicon coated magnetic plate, a filament in said vacuum tube, a line 87 leading from said coil 85 to said filament, a galena magnetic plate in said vacuum, a line leading therefrom to a receiver and a line common to said lines 78 and 87 with a resistance of 15 several megohms therein forming a balancing means for said lines 78 and 87.

15. In a system of the class described, an energy transformer, a transmission line leading from said energy transformer, a variable magnetic coil 71 to which said line leads, another variable magnetic coil 76, a line leading from coil 71 to coil 76, a vacuum tube, a platinum plate therein, a line 78 leading from said coil 76 to said platinum plate, a resistance in said vacuum, another variable magnetic coil 85, a line 84 leading therefrom to said resistance, a silicon coated magnetic plate in said vacuum, a line leading from said line 78 to said silicon coated magnetic plate, a filament in said vacuum tube, a line 87 leading from said coil 85 to said filament, a galena coated magnetic plate in said vacuum, and a line leading therefrom to a receiver, in combination with a line connected to said line 84 and having a crystal rectifier and a battery therein.

16. In a system of the class described, an energy transformer, a transmission line leading from said energy transformer, a variable magnetic coil 71 to which said line leads, another variable magnetic coil 76, a line leading from coil 71 to coil 76, a vacuum tube, a platinum plate therein, a line 78 leading from said coil 76 to said platinum plate, a resistance in said vacuum, another variable magnetic coil 85, a line 84 leading therefrom to said resistance, a silicon coated magnetic plate in said vacuum, a line leading from said line 78 to said silicon coated magnetic plate, a filament in said vacuum tube, a line 87 leading from said coil 85 to said filament, a galena coated magnetic plate in said vacuum, a line leading therefrom to a receiver, a line common to the lines 78 and 87 and having a resistance therein of substantially 12 megohms forming a balancing means for said lines 78 and 87, and a line connected to said line 84 and having a crystal rectifier and a battery therein.

17. In a system of the class described, an energy transformer, a transmission line leading therefrom, a variable magnetic coil 71 connected to said line, another variable

magnetic coil 76, a line leading from coil 71 to coil 76, a vacuum tube, a platinum plate therein, a line 78 leading from said coil 76 to said platinum plate, a resistance in said vacuum tube, another variable magnetic coil 85 a line leading therefrom to said resistance, a filament in said vacuum tube, a line 87 leading from said coil 85 to said filament, a silicon coated magnetic plate in said vacuum tube, a line leading from said line 78 to said silicon coated magnetic plate and having a condenser therein, a galena coated magnetic plate in said vacuum tube, a receiver, a line leading from said filament and from said galena coated plate to said receiver and a line in said receiver circuit having a variable condenser therein.

18. In a system of the class described, an energy transformer, a transmission line leading therefrom, a variable magnetic coil 71 connected to said line, another variable magnetic coil 76, a line leading from coil 71 to coil 76, a vacuum tube, a platinum plate therein, a line 78 leading from said coil 76 to said platinum plate, a resistance in said vacuum tube, another variable magnetic coil 85, a line leading therefrom to said resistance, a filament in said vacuum tube, a line 87 leading from said coil 85 to said filament, a silicon coated magnetic plate in said vacuum, a line leading from said line 78 to said silicon coated magnetic plate and having a condenser therein, a galena coated magnetic plate in said vacuum tube, a receiver, a line from said filament and from said galena coated plate to said receiver, a line in said receiver circuit having a variable condenser therein, and a balancing line between the lines 78 and 87 provided with a resistance of approximately 12 megohms 105 therein.

19. In a system of the class described, an energy transformer, a transmission line leading therefrom, a variable magnetic coil 71 connected to said line, another variable magnetic coil 76, a line leading from said coil 71 to said coil 76, a vacuum tube, a platinum plate therein, a line 78 leading from said coil 76 to said platinum plate, a resistance in said vacuum tube, another variable magnetic coil 85, a line leading therefrom to said resistance, a filament in said vacuum, a line 87 leading from said coil 85 to said filament, a silicon coated magnetic plate in said vacuum tube, a line leading from said line 78 to said silicon coated magnetic plate and having a condenser therein, a galena coated magnetic plate in said vacuum tube, a receiver, a line leading from said filament and from said galena coated plate to said receiver, a line in said receiver circuit having a variable condenser therein, a balancing line between the lines 78 and 87 and provided with a resistance of approximately 12 megohms, a condenser in 130

said line 84 and a line connected with said line 84 on opposite sides of said condenser and provided with a resistance of approximately 2 megohms.

5 20. The combination of a primary coil, a transmitter in series therewith, a secondary coil, the latter being composed of independent coils each composed of turns half of which are wound clockwise and the other 10 half counter clockwise, and an intermediate coil similarly wound, condensers for the terminals of said plurality of coils, a vacuum tube containing a resistance coil, a filament and a plurality of plates, two of 15 which are composed of magnetic material, lines leading from said secondary coil to said vacuum tube, a line leading from one of said magnetic plates out from said tube and means for excluding from said last mentioned line, all appreciable electric oscillations and current.

21. In a system of the character stated, means for transmitting and receiving intelligence through a single ungrounded metallic 25 conductor, and means for excluding all appreciable electric oscillations and current from said conductor.

22. In a system of the character stated, the combination of a telephone transmitter, 30 a telephone receiver, a single ungrounded conductor common thereto, means for transmitting intelligence therebetween over said ungrounded conductor, and means for excluding all appreciable electric oscillations 35 and current from said single ungrounded conductor intermediately of said transmitter and receiver.

23. In a system of the character stated, the combination of a telephone transmitter, a 40 telephone receiver, a single ungrounded line

common to said transmitter and receiver, means for transmitting intelligence over said line, and means including a resistance of the order of several megohms for excluding all appreciable electric oscillations and 45 current from said single line.

24. In a system of the character described, an energy transformer, comprising a secondary coil, composed of a plurality of independent coils and an intermediate coil, 50 all of said coils being composed of turns wound one half clockwise and the other half counter clockwise, condensers for the terminals of each of said coils, a vacuum tube, containing a platinum plate, a magnetic 55 plate, a resistance coil, a filament and another magnetic plate in the order named, lines leading from said secondary coil to said vacuum tube, a receiver, a line leading from said tube to said receiver and means 60 for excluding from said latter line all appreciable electric oscillations and current.

25. In a system of the character described, an energy transformer, comprising a secondary coil, composed of a plurality of 65 independent coils and an intermediate coil, all of said coils being composed of turns wound one half clockwise and the other half counter clockwise, condensers for the terminals of each of said coils, a vacuum tube, 70 containing a plurality of electrodes, lines leading from said secondary coil to said vacuum tube, a receiver, a line leading from said tube to said receiver, and means for excluding from said latter line all appreciable electric oscillations and current.
